(57) **CLAIM**

The ornamental design for a lamp, as shown and described.

DESCRIPTION

FIG. 1 is an isometric view of a lamp in accordance with the new design;

FIG. 2 is a front elevational view of the lamp in FIG. 1, whereby the opposing side is a mirror image thereof;

FIG. 3 is a right side elevational view of the lamp in FIG. 1, whereby the opposing side is a mirror image thereof;

FIG. 4 is a top plan view of the lamp in FIG. 1;

FIG. 5 is a bottom view of the lamp in FIG. 1;

FIG. 6 is an isometric view of the lamp as shown in FIG. 1 without the shade removed for ease of illustration;

FIG. 7 is a front elevational view of the lamp in FIG. 6;

FIG. 8 is a rear elevational view of the lamp in FIG. 6;

FIG. 9 is a right side elevational view of the lamp in FIG. 6;

FIG. 10 is a left side elevational view of the lamp in FIG. 6;

FIG. 11 is a top plan view of the lamp in FIG. 6; and,

FIG. 12 is a bottom view of the lamp in FIG. 6.

Broken lines in the drawing form no part of the design to be patented.
